UNITED STATES PATENT OFFICE.

HOMER V. CLUTTER, OF DENVER, COLORADO.

COMBINED HEAT AND STEAM GENERATOR.

1,243,812.

Specification of Letters Patent. Patented Oct. 23, 1917.

Application filed June 4, 1917. Serial No. 172,611.

To all whom it may concern:

Be it known that I, HOMER V. CLUTTER, a citizen of the United States, residing at Denver, in the county of Denver and State of Colorado, have invented certain new and useful Improvements in Combined Heat and Steam Generators, of which the following is a specification.

This invention relates to an apparatus for utilizing water, liquid fuel and air and gaseous fuel for generating an expansive element for use in driving machinery, heating buildings or other useful purposes, and has for its object, broadly, to provide a construction which will consist of few and simple parts, will economically produce superheated steam, will utilize the force of expanded air and exhaust gases as well as steam and will occupy a limited space in proportion to the degree of heat and quantity of steam generated, as compared with other means.

The invention includes a container for ignited hydrocarbon to produce heat and expanded gases, said container being disposed in and surrounded by a water receptacle, whereby steam will be generated and the heat of the container conserved. The invention consists of the novel construction, combination and arrangement of parts as described herein and claimed, and as illustrated in the accompanying drawing, wherein,—

Figure 1 is a view of the apparatus in longitudinal section. Fig. 2 is a view in transverse section through the middle of the apparatus, as on line 2—2 of Fig. 1. Fig. 3 is a sectional view through the screw-plug for the fuel intake and sleeve of the combustion chamber. Fig. 4 is a transverse section of the same, as on line 4—4 of Fig. 3.

Referring now to the drawing for a more particular description, numeral 5 indicates a stationary receptacle or boiler for containing water, and of such required construction that steam may be generated therein, its upper part being provided with a dome 6.

Disposed within the boiler is a combustion chamber 7, its wall 8 being supported by and maintained above the bottom of

the boiler by any suitable means, as by brackets 9 and a pipe-section 10. At one end of the combustion chamber and communicating therewith is a sleeve 11 which traverses the wall of the boiler, the outer end of said sleeve being provided with a screw-plug 12.

The screw-plug is provided with an intake pipe 13 for admitting air under pressure to the chamber 7, the degree of said air pressure being greater than the degree of steam pressure in the boiler. Numeral 14 indicates a pipe for the intake of liquid fuel under pressure, said pipe extending within 65 and having its convergent discharge terminal disposed adjacent to the end of the pipe 13.

The container 8 is provided with a vertically disposed conducting pipe 15, its upper end terminating above the water-level of the boiler and preferably projecting upwardly within the dome, the lower end of said conducting pipe being in communication with the chamber 7 and the pipe-section 10, and, 75 preferably, disposed in line with and terminating near the end of said pipe-section.

At 16 is indicated a valve-housing having a valve seat 17 and a valve 18, said valve-housing being threaded on a tubular part 80 19 which is threaded in the pipe-section 10; and at 20 is indicated a line pipe normally in communication with the chamber 21 of the receptacle 5 and chamber 7, subject to the control of the valve 18.

Any suitable means may be employed for igniting the hydrocarbon in the combustion chamber, the means shown herein being the spark-plug 22 which is mounted in the screw-plug 12, said spark-plug being operated by any suitable source of electrical supply, one of its electrical conductors being indicated at 23.

On account of the water-sealed connection of the conducting pipe 15 with the upper part of the wall 8, water from the chamber 21 will not enter the combustion chamber, and it is obvious that the heat generated in said chamber will not be directly lost to the atmosphere by radiation. 100 Water is supplied to the receptacle 5 by means of the supply pipe 24.

In operation, air compressed by any suitable means is introduced to the chamber 7, the degree of compression of the air being sufficient to cause it to pass the check valve 25 and pipe 18 against the resisting pressure of steam and expanded elements within said chamber. Liquid fuel under pressure will also pass the check valve 26 and will be atomized or finely divided when it passes through the convergent terminal of the pipe 14. The hydrocarbon within the chamber 7 will be ignited, and the combustion will cause steam to be generated. The valve 18 being open, steam will pass from the dome through the pipe 15, pipe-section 10 and line-pipe 20 for driving machinery or for heating purposes.

During operation, after the hydrocarbon in the chamber 7 is ignited, combustion will continue without interruption, the chamber being supplied with air and liquid fuel, as first described. The heated exhaust gases will move from the chamber 7 to pipe 20 with the steam and will become intermixed therewith while passing through the pipe-section 10, and it will be understood that, on account of the heat in the combustion chamber the pipe 15 will become intensely heated. The steam will be exposed to the heat of pipe 15 while being conducted therein and will be superheated, the construction being such that the steam will be conducted through the combustion chamber substantially to the intake of the pipe-section 10, approximately all of the heat generated in the combustion chamber being utilized.

Having fully described my invention, what I claim and desire to secure by Letters Patent is,—

1. In a combined heat and steam generator, a line pipe, a water receptacle, a combustion chamber within the water receptacle provided with an intake for compressed air, an intake for liquid fuel under pressure and having a pipe-section communicating with the line pipe, an upright conducting pipe communicating with and having its intake disposed above the water receptacle and having its discharge port disposed within the combustion chamber adjacent to the pipe section, and devices for igniting the contents of the combustion chamber.

2. In a combined heat and steam generator, the combination of a line pipe, a water receptacle provided with a dome, a combustion chamber below the dome within the receptacle, said chamber having an intake for compressed air, an intake for liquid fuel under pressure and having a pipe-section communicating with the line pipe, devices for igniting the contents of said combustion chamber, and an upright conducting pipe in communication with the combustion chamber and with the dome of the water receptacle, said conducting pipe being disposed in line with the pipe-section.

3. In a combined heat and steam generator having a line pipe, a cylindrical water receptacle provided with a dome, a cylindrical combustion chamber circumscribed by the water receptacle, said chamber being provided with a radially disposed pipe-section communicating with the line pipe and having an intake for compressed air and an intake for liquid fuel under pressure, a conducting pipe disposed in line with the pipe-section and having its intake terminal disposed in said dome, its discharge terminal being disposed near the lowermost part of the combustion chamber, adjacent to said pipe-section.

4. In a combined heat and steam generator, a water receptacle, a second receptacle for containing ignited hydrocarbon, said second receptacle being provided with intake pipes and being disposed within the water receptacle for converting the water into steam, a line pipe, a pipe-section communicating with the second receptacle and the line pipe, and an upright pipe for conducting steam from the water receptacle to the second receptacle for a movement of steam to the line pipe by moving through the pipe-section, said upright pipe having an imperforate wall throughout its entire length and having its intake disposed above the water receptacle.

5. In a combined heat and steam generator, a water receptacle, a second receptacle for containing a heating element, said second receptacle being disposed within and surrounded by the walls of the water receptacle for converting the water into steam, tubular members traversing the wall of the water receptacle for conducting fluids under pressure to the second receptacle, a line pipe, a pipe-section having a uniform bore in communication with the second receptacle and the line pipe, and an upright pipe having its intake disposed above the water receptacle and traversing a wall of and extending substantially through the second receptacle for conducting steam from the water receptacle to discharge it at the lower part of the second receptacle for a movement thereof to the line pipe by passing through the pipe-section.

6. In a combined heat and steam generator, a receptacle for containing water and provided with a dome, a second receptacle for containing ignited hydrocarbon and adapted to be disposed in the water circumscribed by the walls of the first named receptacle for causing the water to be converted into steam, pipes traversing a wall of the first named receptacle for conducting fluids to the second receptacle, a line pipe, a pipe section communicating with the sec-

ond receptacle and the line pipe, an upright pipe for conducting steam from said dome to the second receptacle for a movement of said steam and the products of the ignited hydrocarbon of said second receptacle to the line pipe by moving through the pipe section, said conducting pipe being disposed substantially in alinement with the pipe sec-

tion, and a valve for controlling a communication of the pipe-section with the line pipe. 10

In testimony whereof, I have affixed my signature in presence of two witnesses.

HOMER V. CLUTTER.
